UNITED STATES PATENT OFFICE.

JOHN M. SULLIVAN, OF CULVER, INDIANA.

WATER-TUBE BOILER.

Original application filed August 26, 1920, Serial No. 406,113. Divided and this application filed October 26, 1923. Serial No. 670,821.

To all whom it may concern:

Be it known that I, JOHN M. SULLIVAN, a citizen of the United States, residing at Culver, in the county of Marshall and State 5 of Indiana, have invented certain new and useful Improvements in Water-Tube Boilers, of which the following is a specification.

This invention pertains in general to steam boilers, this application being a division of 10 my United States Letters Patent No. 1,473,712, granted November 13, 1923, for water tube boilers.

One of the primary purposes of this invention is to provide a boiler with baffles so connected that a continuous circulation of water through them will be maintained so as to prevent the baffles from burning out, the baffles being connected in a closed circuit, including a feed water heater, so that the 15 heat units absorbed by the water in the baffles will be transmitted to the feed water en route to the boiler, thereby conserving these units.

Another object of the invention is the provision of water cooled baffles which will not become clogged with sediment and sludge, such as customarily collects in baffles to which fresh water is continuously supplied, and in which scale and other deposits likely 20 to detract from the efficiency of the apparatus will not collect by reason of the fact that the same water is continuously circulated through the baffles in a closed circuit.

Another purpose of the invention is to so arrange the baffles that the water flow therein will be in a direction counter to the direction of passage of products of combustion around the baffles, thereby promoting a high efficiency of the boiler.

On the accompanying drawing, the single figure of which is a longitudinal view partially in section of a boiler embodying my invention, the boiler is represented as of the usual tube type comprising the tubes 3, 40 mounted in and connected to the front and rear headers 4 and 5, respectively, which headers are in turn connected with the steam drum or cylinder 6 disposed above the tubes. The fire box 7 is located as usual beneath the tubes above the grates 8, the ash pit 9 being disposed beneath the grates, and access to the fire box and to the ash pit being obtained 45 through the doors 11 and 12 respectively. The products of combustion are delivered 50 through the outlet flue 13 connected to a chimney or stack in the usual manner.

Between the fire box and the flue are located a plurality of baffles, indicated by reference characters 14 and 15 respectively, and, as will be apparent from the drawings, 60 these baffles are disposed in spaced relation between the ends of the boiler tubes; the rear baffle 15 extends from the drum 6 in a substantially vertical plane downwardly a short distance beneath the lowermost tube 3, while 65 the front baffle extends upwardly from a point in proximity to the fire box to a point slightly above the uppermost tube 3. Each baffle is of hollow construction and is provided with a series of transversely disposed 70 thimbles 16 forming a water tight connection with the walls of the baffle, the thimbles being of suitable size to accommodate the water tubes 3, which extend therethrough and fit loosely therein. This construction 75 permits the ready removal and replacement of the tubes when necessary for repairs or other purposes without interference by the baffles. The lower ends of the baffles are connected by one or more pipes 17, as shown. 80

Above the drum 6, or in any suitable position relatively thereto, is mounted a feed water heater 18, of well-known or preferred construction, preferably comprising a closed cylindrical drum provided with headers 19 and 21 spaced a short distance from the ends thereof, and connected by water tubes 22, through which water flows from end to end of the heater. A horizontally disposed partition 23 precludes direct flow of water from 85 the top to the bottom, or vice versa, of the space at one end of the heater between the header 19 and the end of the drum. The fresh water to be delivered to the boiler enters the heater from any suitable source 90 through the pipe 24, thence flows to the opposite end of the heater, thence upwardly and backwardly and is delivered to the drum 6 of the boiler through the pipe 25. 95

The upper end of the rear baffle 15 is connected with the bottom of the feed water heater by a pipe 26 and the upper end of the other baffle 14 is connected to the top of the heater by a pipe 27. Both pipes 26 and 27 connect with the chamber of the feed water 100 heater surrounding the tubes 22, and the water surrounding these tubes will heat the water flowing through the tubes.

In the operation of my invention the products of combustion rising from the fire box 110 7 pass upwardly in front of the forward baffle 14, thence over the baffle downwardly

between the baffles, thence rearwardly beneath the rear baffle and thence upwardly to the outlet flue. The water tubes 3 and the water therein are heated by these products of combustion and likewise the water in the baffles 14 and 15 is also heated. Since the baffle 14 is located in the hottest part of the furnace, the water therein will be highly heated, will rise through the pipe 27 and be delivered into the feed water heater 18. Here, flowing downwardly around the tubes 22, it will give up a considerable proportion of its heat to the fresh water flowing to the boiler, and the cool water will flow downwardly through the pipe 26 into the rear baffle 15, where it will become again partially heated and will then flow through pipes 17 into the forward baffle to be further heated.

20 The baffles are connected in a closed circuit, which is initially filled with clean fresh water. This water is continuously circulated and is heated in the baffles and gives off its heat to the feed water in the feed water heater. Since the same water is continuously being circulated and reheated it will be observed that scale, sludge and other deposits which customarily collect in water cooled baffles through which new water is continuously flowing, will collect only in very minute quantities, if at all. The efficiency of the baffles and their heat conducting properties is, therefore not diminished with continued use; but, on the other hand, a high degree of efficiency is at all times maintained. The baffles are effectively cooled by the water therein so that liability of their burning out is reduced to a minimum and all of the heat units absorbed through the baffles are conserved and transferred to the boiler feed water.

The structural details illustrated and described may obviously be varied within considerable limits without exceeding the scope 45 of the invention as defined in the following claims.

I claim:

1. In a water tube boiler, the combination of a plurality of water tubes, a fire box beneath the forward end of said tubes, a steam drum above and communicating with said tubes, a front hollow baffle and a rear hollow baffle intermediate the ends of said tubes, the front baffle being adjacent the fire box and so spaced as to permit the products of combustion to pass above the same, the rear baffle being so spaced as to permit the said products to pass between it and the front baffle and then beneath the same, means providing communication between the hollow interiors of said baffles at their lower ends, a feed water heater, and pipes connecting said heater and said baffles together to form a closed circuit.

2. In a water tube boiler, the combination of a plurality of water tubes, a front hollow baffle and rear hollow baffle intermediate the ends of said tubes and dividing the said boiler into three distinct gas passageways, a fire box beneath the first passageway, means providing communication between the hollow interiors of said baffles at their lower ends, a feed water heater, and pipes connecting said heater and the interiors of said baffles to form a closed circuit.

3. In a water tube boiler, the combination of a plurality of water tubes, a front hollow baffle and rear hollow baffle intermediate the ends of said tubes and dividing the said boiler into three distinct passageways for the circulation of the products of combustion around said tubes, a fire box beneath the first passageway, means providing communication between the hollow interiors of said baffles at their lower ends, a feed water heater having a plurality of tubes for circulating feed water, and pipes connecting the interior of said heater around said tubes and the interior of said baffles to form a closed circuit for the flow of heated water from said baffles to raise the temperature of said feed water.

J. M. SULLIVAN.
